UNITED STATES PATENT OFFICE.

CORNELIUS B. CORCORAN, DECEASED, LATE OF NEW YORK, N. Y.; BY MICHAEL J. CORCORAN, ADMINISTRATOR, OF NEW YORK, N. Y., ASSIGNOR TO UNDERWOOD TYPEWRITER COMPANY, OF NEW YORK, N. Y., A CORPORATION OF DELAWARE.

TYPEWRITING MACHINE.

Application filed March 24, 1924. Serial No. 701,398.

To all whom it may concern:

Be it known that CORMELIUS B. CORCORAN, deceased, late a citizen of the United States, and late residing in the borough of Bronx, county of Bronx, city and State of New York, invented certain new and useful Improvements in Typewriting Machines, of which the following is a specification.

This invention relates to improvements in typewriting machines, particularly to type-bar cushions for the purpose of reducing the noise created by the impact of the type-bars against the stop-ring when operating the machine.

One of the objects of the invention is to improve and simplify the construction of type-bar cushions to make them more efficient and durable.

Other objects are to facilitate the assembling of the parts of the type-bar cushion, to secure the parts against accidental displacement or loss, and to make the sundry parts thereof readily displaceable when worn out.

Other features and advantages will hereinafter appear.

In the accompanying drawings,

Figure 1 is a front view in elevation, showing one form of the improved type-bar cushion in position on the type-segment which is shown as situated below and forwardly of the platen, which is diagrammatically illustrated with one of the type-bars in contact therewith.

Figure 2 is a vertical section on the line 2—2 of Figure 1, looking from left to right, and showing also a diagrammatic illustration of the platen and a type-bar in two positions, to wit: in its normal position before it is actuated by the operator, and in its operative position when it is brought with the type thereon into contact with the platen.

Figure 3 is an enlarged view, mainly in section, of the type-bar cushion and type-segment as shown in Figure 2, and also showing a detached section of the connection of the stop-ring of said cushion with springs at the rear of the type-segment.

Figure 4 is a vertical section on the line 4—4 of Figure 3 across the bolts of the stop-ring of the type-bar cushion, looking from right to left, and showing the springs and lock-nuts in elevation.

Figure 5 is a front view in elevation of a modified form of the type-bar cushion, shown as connected to the type-segment.

Figure 6 is a section on the line 6—6 of Figure 5, looking in the direction of the arrows.

11 designates the platen of a typewriting machine of the Underwood type, and 12 the shaft thereof, which is shown in cross-section in Figure 2.

To provide a cushion for the type-bars 13, in the form of the type-bar cushion shown in Figures 1 to 4, inclusive, a groove 15 is formed in the front face of the type-segment 16, which is shown in Figure 2 as having therein the pivots 31 for connecting the type-bars 13 thereto, to receive a lining 17, which is preferably channel shaped, as shown in Figures 2 and 3, and which is preferably made of felt; but it may also be made of some shock-absorbing material other than felt.

The longitudinal outline of the groove 15 and lining 17 is shown in Figure 1 as that of an arc of a circle concentric with the segment 16. The lining 17 envelops the rear part of a stop-ring 18—19, which is imbedded therein, and serves to absorb the shock received from said stop-ring and check the transmission of said shock to the segment 16. The stop-ring 18—19 consists of an outer tube 18 and a core or filling 19. The tube 18 is preferably made of steel, but it may also be made of some resilient metal other than steel, and it is preferably square or rectangular in cross-section, as shown in Figures 2 and 3. The core 19 preferably consists of lead with which said tube 18 may be filled; but some plastic metal or material other than lead may be employed to fill the outer tube 18 if desired.

The rear wall of the tube 18 serves to distribute the shock received by the stop-ring 18—19 over a large area of the lining 17. The front wall of the tube 18 serves as a resilient medium to receive the impact from the type-bars 13 and transmit the same to the lead core 19, which is provided for the purpose of deadening the noise of the impact of the type-bars 13 against the tube 18.

To gently hold said stop-ring 18—19 against the lining 17 in said groove 15, the tube 18 is provided on the rear thereof with stud-bolts or rivets 20, which pass through

bolt-holes 21 in the segment 16 and are connected to slotted springs 22 by means of lock-nuts 23.

- Said springs 22 are shown in Figures 2 and 3 as secured to the type-segment 16, at the rear thereof, by means of screws 24, and they have therein slots 25, as clearly shown in Figures 3 and 4, to receive the forward or interlocking ends 26 of the lock-nuts 23.
- 10 Said ends 26 are shown in Figure 4 as square in outline, and the flat sides thereof are tapered, as shown in Figures 3 and 4. The flat sides of said ends 26 are interlocked with the sides of the slots 25 in said springs 22, whereby the nuts 23, 26 are kept from rotating and getting loose on the bolts 20.

The taper on the flat sides of said ends 26 serves to facilitate the adjustment of said ends 26 in position in said slots 25.

- 20 To remove the stop-ring 18-19 for inspection or renewal, the upper ends of the springs 22 may be deflected by hand to release the lock-nuts 23, 26, which may then be removed from the bolts 20, which may 25 then in turn be removed from the bolt-holes 21, thereby removing the stop-ring 18-19 from said lining or seat 17 in the groove 15.

In the modification of the type-bar cushion shown in Figures 5 and 6, the stop-ring 28-29 consists of the channel-shaped member 28, which is preferably made of steel or some other resilient metal. It is shown as secured to the segment 16, which is 30 shown in Figure 6 as having therein the pivot 31 for the type-bars, by means of the screws 30, and it has a filling of lead 29 enclosed between the concave part thereof and the front face of said segment. The front wall 28^a of the stop-ring 28-29 serves 40 to intercept the type-bars of the typewriting machine and to check the impact of the same; and the lead filling 29 in the rear of said wall serves to deaden the noise of the impact.

- 45 The modification shown in Figures 5 and 6 is evidently very simple and inexpensive.

Variations may be resorted to within the scope of the invention, and portions of the improvements may be used without others.

50 Having thus described the invention, I claim:

1. In a typewriting machine, the combination of a platen, a type-segment, type-bars pivotally connected to the segment 55 in position to strike the platen, and a type-bar cushion, comprising a groove in the front face of the segment, a channel-shaped lining of shock-absorbing material in said groove, and a stop-ring having its rear part 60 imbedded in said lining in said groove and its front part extending forwardly of said segment to intercept the type-bars and check the impact thereof.

2. In a typewriting machine, the combination of a platen, a type-segment, type-

bars pivotally connected to the segment in position to strike the platen, and a type-bar cushion, comprising a groove in the front face of the segment, and a channel-shaped lining of shock-absorbing material 70 in said groove, combined with a stop-ring, consisting of a tube of resilient metal filled with plastic metal, said stop-ring having its rear part imbedded in said lining in said groove and its front part extending forwardly of the segment to intercept the type-bars and check the impact thereof.

3. In a typewriting machine, the combination of a platen, a type-segment, type-bars pivotally connected to said segment in 80 position to strike the platen, and a type-bar cushion, comprising a groove in the front face of said segment, and a channel-shaped lining of shock-absorbing material in said groove, combined with a stop-ring 85 consisting of a steel tube filled with lead, said stop-ring having its rear part imbedded in said lining in said groove and its front part extending forwardly of the segment to intercept the type-bars and check the impact thereof.

4. In a typewriting machine, the combination of a platen, a type-segment, type-bars pivotally connected to said segment in 95 position to strike the platen, and a type-bar cushion, comprising a groove in the front face of the segment, and a channel-shaped lining of shock-absorbing material in said groove, combined with a stop-ring 100 consisting of a flat-sided tube of resilient metal filled with plastic metal, said stop-ring having its rear part imbedded in said lining in said groove and its front part extending forwardly of said segment to intercept the type-bars and check the impact thereof.

5. In a typewriting machine, the combination of a platen, a type-segment, type-bars pivotally connected to the segment in 110 position to strike the platen, and a type-bar cushion, comprising a groove in the front face of said segment, a channel-shaped lining of felt in said groove, and a stop-ring having its rear part imbedded in said lining in said groove and its front part 115 extending forwardly of said segment to intercept the type-bars and check the impact thereof.

6. In a typewriting machine, the combination of a platen, a type-segment, type-bars pivotally connected to said segment in position to strike the platen, and a type-bar cushion, comprising a groove in the front face of said segment, a lining of shock-absorbing material in said groove, and a stop-ring having its rear part imbedded in said lining in said groove and its front part 120 extending forwardly of said segment to intercept the type-bars and check the impact thereof, combined with suitable springs for 125 130

gently holding said stop-ring against said lining in said groove.

7. In a typewriting machine, the combination of a platen, a type-segment, type-bars pivotally connected to said segment in position to strike the platen, and a type-bar cushion, comprising a groove in the front face of said segment, a lining of shock-absorbing material in said groove, and a stop-ring having its rear part imbedded in said lining in said groove and its front part extending forwardly of said segment to intercept the type-bars and check the impact thereof, combined with rearwardly-extending bolts on said stop-ring, and springs situated at the rear of said segment, said springs drawing on said bolts, thereby gently holding said stop-ring against said lining in said groove.

8. In a typewriting machine, the combination of a platen, a type-segment, type-bars pivotally connected to said segment in position to strike the platen, and a type-bar cushion, comprising a groove in the front face of said segment, a lining of shock-absorbing material in said groove, and a stop-ring having its rear part imbedded in said lining in said groove and its front part extending forwardly of said segment to intercept the type-bars and check the impact thereof, combined with rearwardly-extending bolts on said stop-ring, suitable nuts on said bolts, and plate springs situated at the rear of the segment and pressing rearwardly against said nuts, thereby drawing on said bolts to gently hold said stop-ring against said lining in said groove.

9. In a typewriting machine, the combination of a platen, a type-segment, type-bars pivotally connected to said segment in position to strike the platen, and a type-bar cushion, comprising a groove in the front face of said segment, a lining of shock-absorbing material in said groove, and a stop-ring having its rear part imbedded in said lining in said groove, and its front part extending forwardly of said segment to intercept the type-bars and check the impact thereof, combined with rearwardly-extending bolts on said stop-ring, nuts on said bolts, plate springs situated at the rear of the segment and pressing rearwardly against the nuts, thereby drawing on said bolts to gently hold said stop-ring against said lining in said groove, slots in said springs, and flat sides on parts of said nuts to interlock with said slots to prevent accidental displacement of said nuts.

10. In a typewriting machine, the combination of a platen, a type-segment, type-bars pivotally connected to said segment in

position to strike the platen, and a type-bar cushion comprising a groove in the front face of said segment, a lining of shock-absorbing material in said groove, and a stop-ring having its rear part imbedded in said lining in said groove and its front part extending forwardly of said segment to intercept the type-bars and check the impact thereof, combined with rearwardly-extending bolts on said stop-ring, nuts on said bolts, plate springs situated at the rear of the segment and pressing rearwardly against said nuts, thereby drawing on said bolts to gently hold said stop-ring against said lining in said groove, slots in said springs, flat sides on parts of said nuts to interlock with said slots to prevent accidental displacement of said nuts, and bevels on said flat sides to facilitate the adjustment of said sides and said slots.

11. In a typewriting machine, the combination of a platen, a type-segment, type-bars pivotally connected thereto in position to strike the platen, and a type-bar cushion, comprising a groove in the front face of the segment and a stop-ring consisting of a tube of resilient metal filled with a plastic metal, said stop-ring having its rear part imbedded in said groove and its front part extending forwardly of the segment to intercept the type-bars and check the impact thereof.

12. In a type-bar cushion of a typewriting machine containing a platen, a type-segment and type-bars, a stop-ring consisting of a tube of resilient metal filled with a plastic metal, said stop-ring extending forwardly of said segment to intercept the type-bars and check the impact thereof.

13. In a type-bar cushion of a typewriting machine containing a platen, a type-segment and type-bars, a stop-ring containing a front wall of resilient metal and a filling of plastic metal in the rear of said wall, said stop-ring extending forwardly of said segment to intercept the type-bars and check the impact thereof.

14. In a type-bar cushion of a type writing machine containing a platen, a type-segment and type-bars, a stop-ring containing a front wall of steel and a filling of lead in the rear of said wall, said stop-ring extending forwardly of said segment to intercept the type-bars and check the impact thereof.

MICHAEL J. CORCORAN,
Administrator of the estate of Cornelius B. Corcoran, deceased.
